US00D581240S

(12) **United States Design Patent**
Glessner et al.

(10) **Patent No.:** US D581,240 S
(45) **Date of Patent:** ** Nov. 25, 2008

(54) **FOLDING KNIFE WITH AN EXTERNAL
OPENING MECHANISM**

(75) Inventors: **Louis S. Glessner**, Evergreen, CO (US);
Craig S. Douglas, Ocean Springs, MS (US);
Tracey H. Rinaldi, Hemet, CA (US)

(73) Assignee: **Spyderco, Inc.**, Golden, CO (US)

(**) Term: **14 Years**

(21) Appl. No.: **29/298,595**

(22) Filed: **Dec. 7, 2007**

(51) **LOC (8) Cl.** 08-03

(52) **U.S. Cl.** D8/99

(58) **Field of Classification Search** D8/99,
D8/98, 107; D22/118; 30/155, 156, 157,
30/158, 159, 160, 161

See application file for complete search history.

(57) **CLAIM**

The ornamental design for a folding knife with an external opening mechanism, as shown and described.

DESCRIPTION

FIG. 1 is a front perspective view of a folding knife with an external opening mechanism, showing my new design in an open position the broken lines representing environment and forming no part of the claimed design;

FIG. 2 is a front elevation view of the invention illustrated in FIG. 1;

FIG. 3 is a rear elevation view of the invention illustrated in FIG. 1;

FIG. 4 is a top plan view of the invention illustrated in FIG. 1;

FIG. 5 is a bottom plan view of the invention illustrated in FIG. 1;

FIG. 6 is a right elevation view of the invention illustrated in FIG. 1;

FIG. 7 is a left elevation view of the invention illustrated in FIG. 1;

FIG. 8 is a front elevation view of the invention illustrated in FIG. 1, in a closed position; and,

FIG. 9 is a rear elevation view of the invention illustrated in FIG. 8 shown in a closed position.

1 Claim, 2 Drawing Sheets
